UNITED STATES PATENT OFFICE

2,529,001

MACHINE FOR THE LIQUID TREATMENT OF TEXTILE MATERIALS

Marcel Cassé, Essonnes, France

Application August 7, 1945, Serial No. 609,374
In France April 28, 1942

Section 1, Public Law 690, August 8, 1946
Patent expires April 28, 1962

3 Claims. (Cl. 68—184)

1

My invention relates to machines for dyeing, bleaching, washing, finishing or the like liquid treatments of textile material, of the type comprising a cylindrical vertical vat with a conical bottom and a perforated false bottom under which a distributor is adapted to rotate round the vertical axis of the vat, an axial propeller sucking the treating bath through the false bottom and forcing it inside the rotary distributor which is provided at its upper part with an aperture which sweeps slowly over the whole of the lower surface of the perforated bottom.

In the machines of this type executed heretofore, the mechanism is arranged in the lower part of the machine it belongs to and the shafts of the propeller and of the distributor enter the vat through stuffing-boxes. This arrangement leads to different drawbacks: leakages at the stuffing-boxes, difficult access and keeping up of the mechanical parts, location of the vat at a high level, etc.

The improvements provided by my invention remove these drawbacks and provide different advantages which will appear from the following description.

According to a first feature of the invention, the whole of the mechanism is carried by a frame above the vat, the propeller shaft and the distributor shaft being concentric and hanging vertically from said mechanism so as to enter freely the treating bath without requiring any stuffing-box.

The distributor shaft, controlled by the mechanism at its upper part is guided at its lower part by a ball or roller bearing of stainless metal arranged inside a stationary tube connecting the center of the perforated bottom with the frame so as to prevent said perforated bottom from sinking under the action of the depression produced by the propeller.

The distributor shaft is preferably tubular so that a portion of the liquid may be forced by the propeller in succession through said shaft, through perforations on the latter and through the inside of the stationary supporting tube and finally through perforations provided in the upper part of said stationary tube, through which perforations this portion of the liquid is poured over the bath. This admission of liquid at the surface of the bath produces horizontal currents which are deflected downwards and submerge the objects to be dyed which might have come floating upwards and carry them towards the bottom.

When the machine includes an admission of heating steam, this admission is preferably provided in the space between the distributor shaft and the stationary supporting shaft, the heating steam condensing in the part of the bath stream directed towards the surface of the bath. Con-

2

sequently, the hottest part of the bath is its upper part and the propeller at the lower part of the machine sucks the liquid at its lowest temperature. The suction and efficiency of the propeller may thus reach their maximum value.

According to a further feature of my invention, a yielding removable packing is secured to the periphery of the upper opening of the distributor and forms a fluidtight joint between said opening and the perforated bottom. It is preferably constituted by one or more thin and yielding blades of stainless metal which may be the same as that used for the whole of the machine. These blades are incurved and are adapted to rub through their free edge against the underside of the perforated bottom.

A drainage sluice valve requiring no welding with the conical bottom of stainless metal is bolted to the center of said conical bottom.

The supporting frame for the mechanism assumes the shape of a C or of a swan's neck and is preferably constituted by electrically welded sectional iron.

Other features of the invention will appear from the following description made with reference to accompanying drawings, given solely by way of example and wherein

Fig. 1 is a vertical cross-section of the machine,

Fig. 2 is a horizontal cross-section through line 2—2 of Fig. 1,

Fig. 3 is a transversal cross-section of the distributor through line 3—3 of Fig. 2,

Fig. 4 is a view at a larger scale of a detail of Fig. 3 and Fig. 5 is a large scale cross-section of the lower bearings.

The machine comprises a cylindrical vat 1 provided with a conical bottom 2, the cylindrical and conical parts being separated by a perforated false bottom 3. A rotary propeller 4 arranged along the axis of the machine has its blades lying approximately in the middle of the height occupied by the conical lower part 5 of the vat.

It sucks the portion of the bath contained in said conical part of the vat and forces it into the rotary distributor 6 concentric with the propeller and provided with a ship's outline as apparent from the drawing. The upper side 7 of this rotary distributor is provided with a diametrical rectangular opening 8 which may be restricted to a half diameter in machines of small capacity. The edges of this rectangular opening 8 are provided with a yielding packing 9 (Fig. 4) which may be for instance of the type disclosed hereinbelow and this packing comes into contact with the underside of the perforated bottom 3. A stationary central tube 10 is at its lower end integral with or rigidly secured to the perforated partition of false bottom 3 while its upper end is integral with or rigidly secured to the cas-

ing 11 which encloses the driving mechanism for the propeller and distributor.

The stationary tube 10 has the advantage of carrying the centre of the perforated bottom and of preventing same from sinking under the action of the depression produced in the conical lower part of the vat by the propeller 4.

Inside the stationary tube 10 is arranged a rotary tube 12 solid with the rotary distributor 6. Said rotary tube 12 is provided at its lower end and preferably at the level of the perforated false bottom 3 with a race 13 (Fig. 5) round which run rollers 14, said rollers running also along an outer race 15 formed by boring the outer stationary tube 10. These rollers carry at each end a trunnion 16, 16a adapted to rotate inside an aperture provided in the corresponding annular part 17 or 17a. This arrangement forms a roller bearing and is entirely made of stainless metal, as are also all the other parts of the machine in contact with the bath.

Inside the inner rotary tube 12 stands tubular shaft 18, to the lower end of which is keyed the propeller 4.

The rotary tube 12 is solid with a part 19 which rotates inside the casing 11. Said part 19 is solid with a worm wheel 20 driven by the worm 21, said worm being itself driven by the worm wheel 22 meshing with a second worm 23 rotating integrally with a pulley 24 operatively connected with the motor 25 through the belt 26.

The propeller shaft 18 rotates inside part 19, preferably with the interposition of two conical ball or roller bearings 27 and 28 and it carries at its upper end a pulley 29 connected with the motor 25 through the belts 30.

A washer 31, provided with a flange for protection against dribbling prevents the grease contained inside part 19 from falling into the bath. Similarly a washer 32, the flange of which also forms a protection against dribbling, prevents the grease from the above described mechanisms from falling into the bath through the opening 33 affording a passage for the rotary tube 12.

The oil, grease and condensation water thus deflected from the upper part of the machine are collected in a channel 34 of stainless metal and poured outside the machine.

Part of the bath forced by the propeller 4 inside the rotary distributor 6 enters the rotary tube 12 and through apertures 35 provided in said tube, passes inside the stationary tube 10. The latter shows openings 36 at a level which is sufficiently high to be substantially above the level surface XX of the dyeing bath. Part of the bath liquid is thus poured over the bath surface. It sweeps said surface and immerses the articles to be dyed in said bath instead of allowing them to float at the surface. The flow of liquid described creates at the same time a downwardly directed current which draws said articles to be dyed towards the bottom of the vat.

The admission of heating steam is effected preferably at the lower part of the central stationary tube 10. To this end, a lateral tube 37 secured to the tube 10, comprises at its upper end an admission for steam 38 and it leads the steam towards the lower part of the tube 10 through apertures 39. This steam mixes with the portion of the bath forced through the inner tubes and heats said portion. The heated bath pours out of the upper part of the machine, as explained hereinabove. By reason of the great turbulency caused by the circulation

of the bath, the temperature has a tendency to become uniform throughout the mass of the bath. However, the propeller 4 sucks the lower part of the bath which is at a lower temperature, which furthers the efficiency of the propeller.

A central sluice valve 40 allows the draining of the machine. The advantage of this central arrangement of the sluice valve is to require the welding of no pipe on to the conical bottom 2 of the vat of stainless steel as the body 40 of the sluice valve may be easily bolted on to the bottom 2.

A C-shaped frame 42 resting on a support 43 carries on one hand the casing 11 and on the other the motor 24. It is preferably constituted by electrically welded sectional iron.

Of course, my invention is by no means limited to the form of execution illustrated and described which has been chosen solely by way of example. Said invention covers all modifications falling within the scope of the following claims.

Having now described my invention what I claim as new and desire to secure by Letters Patent is:

25. 1. A machine for dyeing, bleaching, washing, finishing, and like treatment of textile goods comprising a vat for the treating bath including a cylindrical body having a main bottom and a perforated false bottom above the main bottom, a rotatable hollow distributor having an aperture arranged to sweep the underside of the false bottom, a propeller operable to induce circulation of the bath upwardly through the distributor and those of the perforations in the false bottom overlying the distributor aperture and downwardly from the body through the remaining perforations in the false bottom outlying said distributor aperture, a stationary tube secured to the central portion of the perforated bottom to support and stiffen the latter, drive means for the propeller including a shaft extending upwardly through the tube and drive means for the distributor including a tubular shaft surrounding the propeller shaft and having an open lower end for the admission of the bath and perforations at its upper end for the discharge of the bath, said stationary tube having perforations therein for discharging the bath above the level of the latter in said vat.

50. 2. A machine as claimed in claim 1 further comprising means for admitting steam between the tubular shaft and the stationary tube.

3. A machine as claimed in claim 1 provided with a packing of thin yieldable incurved stainless metal blades secured to the edge of the aperture in said distributor frictionally engaging at their free edges with the underside of the false bottom.

MARCEL CASSÉ.
